UNITED STATES PATENT OFFICE.

JOHN L. DANIELS, JR., OF NEW YORK, N. Y., ASSIGNOR TO AMERICAN CIGAR COMPANY, A CORPORATION OF NEW YORK.

TREATING TOBACCO.

SPECIFICATION forming part of Letters Patent No. 787,611, dated April 18, 1905.

Application filed June 17, 1903. Serial No. 161,865.

To all whom it may concern:

Be it known that I, JOHN L. DANIELS, JR., a citizen of the United States, residing at New York, county and State of New York, have invented certain new and useful Improvements in Treating Tobacco, of which the following is a specification.

The object of the present invention is to render tobacco harmless to the user. As is well known, the injurious effects produced on the heart and nervous system by the use of tobacco are due to the volatile alkaloid nicotine contained in the plant. Various methods have been proposed for rendering the nicotine harmless—as, for example, treating the leaves with tannic acid either alone or in combination with some other substance with the idea of forming an insoluble tannate of nicotine. It has also been proposed by the use of certain oxidizing agents to convert the nicotine into its insoluble and non-poisonous hydroxid-nicotinic acid. In working along this line in experimental and practical applications of my process I have found that nicotine is an extremely stable compound and is not readily oxidized. In fact, it resists the action of all but the strongest oxidizing agents. Ordinary oxygen, hydrogen peroxid, unless in the presence of platinum-black, periodic and perchloric acids, and many other powerful oxidizing agents produce no oxidizing effect whatever on nicotine or its salts. In order to accomplish the oxidation, the oxygen must be "nascent active oxygen," such as is given off by potassium or other permanganate or such as is produced by the silent electric discharge on ordinary oxygen and commonly called "ozone." I prefer to use ozone to effect the desired oxidation, as in that case it is usually unnecessary to expose the tobacco for any length of time to water, which has a solvent or extractive action on some of the good qualities of the plant which it is desirable to retain; but I do not limit myself solely to the use of ozone, for I find that where the tobacco is very strong and contains a relatively large per cent. of nicotine it is advisable to give the leaves a preliminary immersion in a weak solution, preferably, of potassium permanganate before subjecting them to the action of

ozone. Where it is not desirable to oxidize all the nicotine contained in the leaves, I omit either the preliminary treatment with the permanganate or the secondary treatment with ozone.

55

In carrying out the process by the employment of ozone the leaves are exposed to the direct action of the gas in any convenient way, as by blowing the gas on them or by suspending the leaves in an air-tight chamber filled with ozone. To facilitate the action, I first moisten the leaves with a solvent of ozone, such as hypophosphite of soda. The time required for completion of the operation depends upon the per cent. of nicotine present in the leaves. Havana tobacco, which contains a comparatively small proportion of the alkaloid, can be completely denicotized by an exposure of half an hour. Other tobaccos, containing larger amounts of nicotine, must be subjected to longer treatment.

70

The final result of my treatment is nicotinic acid. This compound is substantially harmless, and its presence in smoking and chewing tobacco is not objectionable. Free nicotine, the injurious ingredient of tobacco-smoke, is not produced when tobacco treated by this process is smoked, as is the case with any tobacco treated with tannic acid.

75

My process is also of value in hastening the maturing or curing of tobacco. As the chief object there is to eliminate the gummy and nitrogenous substances in the green leaf by oxidation, the leaves are exposed to the air, fermented, and otherwise worked to oxidize the nitrogenous matters. By applying my process during curing the oxidation of those substances is not only made more rapid, but a part or all of the nicotine may be oxidized at the same time.

90

What I claim is—

The herein-described treatment of tobacco, which consists in moistening the leaves with a solution of hypophosphite of soda, then exposing them to oxygen in the form of ozone, as set forth.

95

JOHN L. DANIELS, JR.
